(57) **CLAIM**

The ornamental design for the luminaire, as shown and described.

DESCRIPTION

FIG. 1 is a bottom front isometric view of our new luminaire design;

FIG. 2 is a top front isometric view thereof;

FIG. 3 is a bottom plan view thereof;

FIG. 4 is a top plan view thereof;

FIG. 5 is a front elevation view thereof;

FIG. 6 is a rear elevation view thereof;

FIG. 7 is a left side elevation view thereof; and,

FIG. 8 is a right side elevation view thereof.

The broken dash lines shown in the drawing views represent non-claimed subject matter, and neither the lines themselves nor anything within the lines form any part of the claimed invention.

1 Claim, 6 Drawing Sheets
